(57) **CLAIM**

The ornamental design for a handheld tripod, as shown and described.

DESCRIPTION

FIG. 1 is a perspective view of a handheld tripod showing my new design where the handheld tripod is in a first configuration of use;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective thereof shown in use with the lamp disposed on the top of the handheld tripod;

FIG. 10 is an enlarged view of portion 10 shown in FIG. 1;

FIG. 11 is a perspective view of the handheld tripod where the handheld tripod is in a second configuration of use;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is another perspective thereof shown in use with the lamp disposed on the top of the handheld tripod; and,

FIG. 20 is an enlarged view of portion 20 shown in FIG. 11. The broken lines shown in the figures depict portions of the handheld tripod and forms no part of the claimed design. The additional broken lines seen in FIG. 9 and FIG. 19 depict environment and forms not part of the claimed design. The

(Continued)

dot-dash broken lines are for the purpose of depicting boundaries of the enlarged portions and forms no part of the claimed design.
